(57) **ABSTRACT**

A new and distinct *chrysanthemum* plant named 'Zanmubonimp' is disclosed, it is characterized by its medium sized, double type blooms with white color ray florets and response time of 7 weeks. The new plant is normally used for commercial cut flower production.

3 Drawing Sheets

1

BACKGROUND OF THE INVENTION

Botanical designation: *Chrysanthemum×morifolium* Ramat.
Cultivar denomination: 'Zanmubonimp'.

RELATED CULTIVARS

'Zanmubonimp' is a mutant plant of 'Zanmubonita' (unpatented).

BACKGROUND OF THE INVENTION

The present invention comprises a new and distinct cultivar of *chrysanthemum*, botanically known as *Chrysanthemum×morifolium*, and referred to by the denomination 'Zanmubonimp'. 'Zanmubonimp' is a product of a breeding and selection program to produce new *chrysanthemum* cultivars for cut flower commercial applications. The new plant cultivar is a naturally occurring whole plant mutant of a parent *chrysanthemum* named 'Zanmubonita' (unpatented). A comparison with the parent plant is made in the section 'description of the invention'. The new cultivar was discovered as a whole plant mutation in June 2015 by Henricus Jacobus Maria Jacobs in a controlled environment (greenhouse) in Valkenburg Z-H, The Netherlands. The first act of asexual reproduction of 'Zanmubonimp' was accomplished when vegetative cuttings were taken from the initial selection and propagated further in Valkenburg Z-H, The Netherlands.

SUMMARY OF THE INVENTION

The present invention is a new and distinct variety of a cut type *chrysanthemum* bearing medium sized double type blooms with white ray-florets and a response time of seven weeks.

2

BRIEF DESCRIPTION OF THE DRAWINGS

The present invention of a new and distinct variety of *chrysanthemum* (of about 10 weeks) is shown in the accompanying drawings, the color being as nearly true as possible with color photographs of this type.

FIG. 1 shows a plant of the cultivar in full bloom.

FIG. 2 shows the various stages of bloom of the new cultivar.

FIG. 3 shows the foliage of the new cultivar.

DESCRIPTION OF THE INVENTION

15 The observations and measurements were gathered from plants grown in August 2016 to March 2017 in a greenhouse in Valkenburg Z-H, the Netherlands in a photo-periodic controlled crop under conditions generally used in commercial practice. The greenhouse temperatures during this crop were at day-time between 18° C. and 25° C. and at night 20° C. After a long day period of 14 days the photo-periodic response time in this crop was 49 days. After the long day period to flowering growth retardants (Alar) were applied 2 to 3 times in an average dose of 2.5 gram/liter water. No tests were done on disease or insect resistance or susceptibility. No tests were done on cold or drought resistance. This new variety of *chrysanthemum* has been found to retain its distinctive characteristics throughout successive propagations however the phenotype may vary significantly with variations in environment such as light intensity and temperature.

35 From the cultivars known to inventor the most similar existing cultivar in comparison to 'Zanmubonimp' is its parent plant 'Zanmubonita'. When 'Zanmubonita' and 'Zanmubonimp' are being compared the following differences and similarities are noticed (1) Stem weight. And (2) Plant

height. (1). Stems of 'Zanmubonimp' are heavier than those of 'Zanmubonita'. (2) Plants of 'Zanmubonimp' are taller than those of 'Zanmubonita'.

The following is a description of the plant and characteristics that distinguish 'Zanmubonimp' as a new and distinct variety.

The color designations are taken from the plant itself. Accordingly, any discrepancies between the color designations and the colors depicted in the photographs are due to photographic tolerances. The color chart used in this description is: The Royal Horticultural Society Colour Chart, sixth edition, 2015.

TABLE 1

Botanical Description of Chrysanthemum x morifolium Ramat. 'Zanmubonimp'		
Bud		
Size:	Medium; cross-section 8 mm, height 7 mm	
Shape:	Round	
Texture:	Pubescent	
Outside color:	Greyed-green 191A	
Phyllaries		
Number:	24, arranged in 3 rows	
Shape:	Elliptic	
Apex:	Acute	
Base:	Truncate	
Margin:	Entire	
Color:	Upper side: Green 136A Under side: Green 137A	
Length and width:	10 mm; 3.5 mm	
Texture:	Pubescent	
Inflorescences		
Spray Form:	Cylindrical	
Inflorescence Type:	Double	
Inflorescence Height:	2 cm	
Inflorescence Diameter:	7-8 cm	
Peduncle length:	10-17 cm	
Peduncle color:	Green 138A	
Peduncle diameter:	2 mm	
Peduncle texture:	Pubescent	
Number per branch:	Approx. 16-17	
inflorescences		
Seeds:	Not observed.	
Fragrance:	Faint chrysanthemum odor	
Color inflorescences		
Center of inflorescence:	Immature stage: Yellow-green 143C; Mature stage: Yellow-green 144C	
Color of upper side of ray florets (outer rows):	White NN155D	
Color of lower side of ray florets (outer rows):	White NN155D	
Color of upper side ray florets (inner rows):	Yellow-green 150D	
Color of lower side ray florets (inner rows):	Yellow-green 150D	
Tonality from distance:	A cut mum with white blooms and a green center	
Color of ray florets after aging of the plant:	White NN155D	
Ray florets		

Type:	Ligulate
Texture:	Upper and under side smooth
Number:	100-110
Shape:	Elliptic
Apex:	Rounded
Base:	Acute
Cross-section:	Weakly concave
Longitudinal axis:	Straight
Length of corolla tube:	2 mm
Ray floret margin:	Entire

TABLE 1-continued

Botanical Description of Chrysanthemum x morifolium Ramat. 'Zanmubonimp'		
5	Ray floret length:	1.8-4 cm
	Ray floret width (outer row):	4-12 mm
	Ratio length/width:	Medium
	Disc florets	
10	Disc diameter:	1 mm
	Distribution of disc florets:	Very few, only visible in mature stage of inflorescence
	Shape:	Tubular
	Color:	Yellow-green 145C at base to Green Yellow 143C at apex
15	Length:	4 mm
	Diameter:	0.5 mm
	Receptacle	
20	Color:	Yellow-green 145D
	Shape:	Domed ised
	Height:	5 mm
	Diameter:	6 mm
	Reproductive Organs	
25	Androecium:	Present on only disc florets
	Stamen length:	3 mm
	Stamen color:	Yellow-green 144A
	Anther color:	Yellow 2A
	Pollen:	Not observed
30	Gynoecium:	Present on both ray and disc florets
	Style color:	Yellow-green 154C
	Style length:	4 mm
	Stigma color:	Yellow 7A
	Stigma width:	1 mm
35	Ovary:	Enclosed in calyx
	Plant	
40	Growth habit:	Upright
	Growth rate:	Medium
	Height:	105-115 cm
	Width:	25 cm
	Stem weight:	65-85 grams
	Stem color:	Green 138B
	Stem texture:	Smooth, slightly pubescent
	Stem diameter:	6-7 mm
45	Stem anthocyanin coloration:	absent
	Internode length:	1.8-2 cm
	Response time:	49 days
	Roots:	Short, fibrous
	Foliation	
50	Glossiness:	Weakly
	Leaf color:	Upper side: Green 136A; Under side: Green 137C
	Color midvein:	Upper side: Yellow-green 147D; Under side: Yellow-green 148D
55	Size:	Medium; length 10-12 cm, width 4.5-6.5 cm
	Quantity per stem:	26-30
	Shape:	Elliptic
	Texture upper side:	Sparsely pubescent
60	Texture under side:	Pubescent
	Venation arrangement:	Pinnate
	Shape of margin:	Serrated
	Shape of base of sinus between lateral lobes:	Rounded
	Margin of sinus between lateral lobes:	Diverging
	Shape of base:	Attenuate to Truncate
65	Apex:	Pointed

TABLE 1-continued

Botanical Description of Chrysanthemum x morifolium Ramat. 'Zanmubonimp'	
Petiole length:	2 cm
Petiole diameter:	2.5-3 mm
Petiole attitude:	Moderately upwards
Petiole color:	Yellow-green 147D
Stipules:	Small

TABLE 2 Differences with the comparison variety,
when grown under identical conditions

	'Zanmubonimp'	'Zamubonita'
5	Stem weight	65-85 grams
	Plant height	105-115 cm

10 I claim:
1. A new and distinct *chrysanthemum* plant named 'Zanmubonimp' as described and illustrated.
